Primary Examiner — Katherine Glennon(74) *Attorney, Agent, or Firm* — William Popejoy(57) **CLAIM**

The ornamental design for a timer, as shown and described.

DESCRIPTION

FIG. 1 is a front elevational view of a timer showing our new design;

FIG. 2 is a rear elevational view thereof;

FIG. 3 is a bottom plan view thereof;

FIG. 4 is a perspective view thereof; and,

FIG. 5 is another perspective view thereof.

The broken lines in the drawings are for the purpose of illustrating portions of the timer that form no part of the claimed design.

The left side of the timer, not shown, is a mirror image of the right side of the timer shown in FIG. 4 and FIG. 5.
